UNITED STATES PATENT OFFICE.

WILLIAM D. COIL, OF MUNCIE, INDIANA.

EGG-CASE FILLER.

Application filed June 18, 1925. Serial No. 37,945.

To all whom it may concern:

Be it known that I, WILLIAM D. COIL, a citizen of the United States, residing at Muncie, in the county of Delaware and State of Indiana, have invented certain new and useful Improvements in Egg-Case Fillers, of which the following is a specification.

This invention relates to improvements in egg case fillers particularly to that type of filler which is made up of series of interlocked strips of straw board or other suitable material.

The object of the invention is to arrange the strips with flats placed between fillers composed of longitudinal and cross strips secured together in such manner that the fillers will be held against longitudinal and lateral movement. It is an improvement on the device shown and described in prior Letters Patent 1,308,578, patented July 1, 1919.

As explained in that prior patent there has been considerable difficulty experienced in the use of egg case fillers from the fact that the eggs are apt to be broken in the transporting of same and especially where they are shipped in cars that endanger the eggs by reason of the jolting of the cars.

This improvement is so constructed that in the event an egg does break, there will be a minimum danger of the contents of the broken egg spreading over adjacent eggs and to this end there is formed on the flat a raised portion so placed in relation to ribs that there are formed troughs for carrying the contents away from the adjacent eggs.

In the accompanying drawings:

Fig. 1 is a perspective view of a case containing a plurality of fillers.

Fig. 2 is a plan view of a portion of the flat.

Fig. 3 is a sectional view on the line $x-x$ of Fig. 2.

Fig. 4 is a sectional view on the line $y-y$ of Fig. 2.

Fig. 5 is a detail view of a longitudinal strip.

Fig. 6 is a detail view of a cross strip.

Referring to the drawings, the case containing the fillers is marked 1 and I have preferably shown a case of such size as to contain five fillers. A filler consists of longitudinal strips and cross strips so connected as to form a plurality of cells and referring to Fig. 1 the longitudinal strip is marked 2 and the cross strip is marked 3. The longitudinal strip is formed with a slotted open-

ing marked 4 and a T-shaped slot 5 while the cross strip is formed with a tongue shaped opening 6, this having a projecting shoulder 7 and these longitudinal and cross strips are interengaged as shown and described in my prior Patent 1,308,578 such that the shoulder 7 is locked in the slot 5 thereby holding the two strips securely locked together while a portion of the cross strips 3 projects above the top of the longitudinal strip. The flat is marked 8 and it is formed with the ribs 9 shown and described in the prior patent and there are shown seven of these ribs extending transversely to the longitudinal strips so that a longitudinal strip placed on top of the flat will have the slot 10 at the bottom of the longitudinal strip engaging on the rib 9 as clearly shown in Fig. 3 and as described in my prior patent. There are raised portions 11 formed on the flat and extending between the ribs. There are trough shaped portions formed between the raised portions 11 and the ribs 9 so that whenever an egg which rests on the raised portion should break the contents will flow into the trough shaped portions and thereby protect adjacent eggs from being marred by the contents of the broken egg.

These raised portions 11 have ribs 12 which extend parallel with the longitudinal strips so that when a longitudinal strip is placed upon the flat the bottom of the longitudinal strip will not only rest on the apex of the rib 9, but will also lie between two of the ribs 12 and thereby the longitudinal strip and the filler of which the longitudinal strip is a part will be held against lateral movement while the contact of the slot 10 in the bottom of the longitudinal strip with the rib 9 will prevent the filler from having any longitudinal movement. There is preferably shown between the ribs formed on the raised portion small raised dot like projections marked 13 and at the center there is preferably shown a small depression 14 and the advantage of these small raised parts is to prevent the egg being broken if it is carelessly dropped within the cell because these little parts 13 will have a tendency to give while the depression 14 will tend to center the egg properly on the raised surface.

It is apparent that the rib 9 not only will accommodate and hold securely the bottom of the longitudinal strip against longitu-

dinal movement, but it will also accommodate the upper portion of the transverse strip which projects within the rib as indicated in Fig. 3 thereby tending to hold 5 the upper portion of the filler below the flat from longitudinal movement. In this manner the filler is very securely held within the case 1 because the longitudinal strip is engaged at its bottom while the top of 10 transverse strip is connected at its top and the longitudinal strips are also engaged at their bottom portions by the parallel ribs of the raised portion to prevent the filler from having any lateral movement.

15 In this way there is disclosed a flat in combination with a filler which locks the filler both at top and at bottom.

Having thus described my invention, I claim:

- 20 1. The method of forming egg case fillers by first forming flats with trough shaped ribs and intermediate raised portions, thereafter assembling said flats with the strips of the fillers, whereby the upper part of one 25 strip will be embraced by said rib and the lower part of a companion strip will embrace a rib of a companion flat, and will also be held on said raised portion, an unobstructed gutter being formed between the 30 ribs and the raised portion.
2. In a device of the character described the combination of a plurality of series of longitudinal and cross strips locked together to form multicell containers, a flat having 35 trough shaped ribs and raised portions intermediate of the ribs, one of said strips on one side of said flat being embraced by the trough shaped rib and a companion strip on the other side of said flat embracing said 40 trough shaped rib, said latter strip being also engaged by the raised portion inter-

mediate of said ribs, whereby an unobstructed gutter will be formed between the rib and the raised portion.

3. In a device of the character described 45 the combination of a plurality of series of longitudinal and cross strips locked together to form a filler with flats having trough shaped ribs and raised portions between the ribs, said raised portions being formed with 50 projecting portions, one strip on one side of each flat being formed to be embraced by said trough shaped rib and a companion strip on the other side of said flat being formed to embrace said rib, said projecting 55 portions of the raised portion being adapted to engage said latter strip whereby the cell case will be securely locked in its assembled position.

4. In a device of the character described 60 the combination of a plurality of series of longitudinal and cross strips locked together to form a filler, a plurality of flats having trough portions and raised portions between the trough portions, the upper part of one strip on one side of each flat being engaged and held by the trough shaped part and a companion strip on the other side of said flat having its bottom portion engaged both by the trough shaped part and also by the 65 raised portion, whereby said latter strip 70 will be locked against movement in two directions.

5. A flat having a plurality of corrugated ribs, raised portions adjacent said ribs, there being troughs between said ribs and raised portions and the raised portions having ribs 75 in their upper surfaces.

In testimony whereof, I have hereunto set my hand this 15th day of June, 1925.

WILLIAM D. COIL.
